UNITED STATES PATENT OFFICE.

GEORGE PAUL THOMAS, OF GLENNSHAW, PENNSYLVANIA.

TOOL-OPERATING MACHINE.

1,175,196.

Specification of Letters Patent. Patented Mar. 14, 1916.

Application filed December 28, 1914. Serial No. 879,276.

To all whom it may concern:

Be it known that I, GEORGE PAUL THOMAS, residing at Glenshaw, in the county of Allegheny and State of Pennsylvania, a citizen of the United States, have invented or discovered certain new and useful Improvements in Tool - Operating Machines, of which improvements the following is a specification.

10 My invention relates to tool-operating machines which are provided with work-carriages to bring to the tool, and by successive step-by-step advances, the material to be operated upon, means being provided to advance the carriage, and stopping mechanism to arrest its movement at predetermined regular or irregular intervals.

15 The object of my invention is to improve the carriage driving and stopping mechanism.

20 A further object is to provide a simple, efficient, and inexpensive construction wherein the tool operating mechanism and the carriage driving and stopping mechanism are so coördinated, that, when the machine has been started a blank of material may be operated upon without further active attention on the part of a workman.

25 Although not limited to machines for any specific purpose, my invention is particularly applicable to machines for punching holes in structural steel plates and sections, and is thus illustrated in the accompanying sheets of drawings, which form part of my 30 specification.

35 Figure 1 is a side elevation of one form of punching machine embodying my invention; Fig. 2 an end elevation, the plane of view being indicated by the line II—II, Fig. 1; Figs. 3 and 4 are side and end views, respectively, of a modification in driving construction; Fig. 5 is a side view to enlarged scale of the driving connections of the machine of Figs. 1 and 2; Fig. 6 a sectional view taken on the line VI—VI, Fig. 5, the uppermost pitman connections being shown in elevation; Fig. 7 a sectional elevation, to enlarged scale, taken on the line VII—VII, Fig. 2, the housing for the stopping mechanism being broken away to show such mechanism; Fig. 8 a plan view of the stopping mechanism as shown in Fig. 7; Fig. 9 a side elevation of a second embodiment of one feature of my invention; and Fig. 10 a plan view of the driving mechanism of the work-carriage shown in Fig. 9.

In the several figures like numerals are used to designate like parts.

The punching machine may be of any suitable construction, that shown in Figs. 60 1 and 2 being particularly adapted for plate-punching purposes, and comprising a frame 1 provided with a reciprocating head 2, to which a pair of punching tools 3 are secured. The head 2 is reciprocated in the usual and 65 well known manner by means of a rotary shaft 4, suitably connected to, or forming a part of, a power shaft 5. Such shaft is provided with a pinion 6, meshing with a pinion 7, secured to a shaft 8, which shaft 70 may be driven continuously in any desired manner, as by a motor 21. A further essential detail of the punching machine consists of dies 9 suitably secured to the frame 1 beneath the punching tools 3.

75 The work-carriage or spacing table also may be of any suitable construction. In the form shown in Figs. 1 and 2 the material to be punched, such as a plate 10, is borne upon a carriage 11, movable upon suitable 80 tracks 12, while in that of Figs. 9 and 10 the material is dragged after the carriage.

85 While, as far as some features of my present invention are concerned, any suitable means may be employed for driving the work-carriage or spacing table, the preferred means (and they form a part of my invention) are characterized by the fact that the driving power continue to act positively to resist or absorb the rebound of the carriage after the stopping mechanism has become effective. Furthermore, in order to quickly and effectively overcome the inertia of the carriage, and to release from the dies the material being operated upon, when, owing to dull tools or for other reasons, burs 90 are formed on such material, two driving means are provided, one for effecting the initial, and the other the concluding, movement of the carriage, the former means being positive and unyielding. In the machine shown in Figs. 1 to 8, inclusive, the carriage-driving power is the power shaft for reciprocating the punching tool, and the connections interposed between such shaft 100 and the carriage are constructed to accomplish the ends just stated.

95 In this machine the carriage is provided along its longitudinal center-line with a rack 13, which meshes with a pinion 14 secured 110 to a driven shaft 15. Such shaft extends through a housing 16, inclosing stopping

mechanism, which will be fully explained hereinafter. The driven shaft is intermittently rotated preferably by means of a pawl-and-ratchet connection from the power shaft to a driving member connected to the driven shaft. There may be a single pawl-and-ratchet connection, as is shown in Figs. 3 and 4, to be presently explained, or two such connections, as shown in Figs. 1, 2, 5 and 6. In the latter, one of the connections acts positively to effect the initial movement of the carriage, and the other acts through a yielding member, preferably a friction clutch, to effect the further and concluding movement; and, in this embodiment of my invention, both are advance movements. While, as just explained, the carriage of Figs. 1 and 2 is driven by a rack, it will be shown in Figs. 9 and 10 may be employed, understood that a carriage of the type and, as shown therein, the driving may be through an endless chain.

The pawl-and-ratchet connections may be of any suitable construction. Having reference first to the unyielding connections for effecting an initial positive movement of the carriage, the power shaft 5, as shown particularly in Figs. 5 and 6, is provided with a pinion 17, which meshes with a second pinion 18, rotatably mounted on the frame 1. To the pinion 18 a pitman 19 is pivotally secured at one end, and at its other end is similarly attached to an arm 20, rotatably mounted on the shaft 15. The arm 20 is provided with a pawl 22 adapted to engage a ratchet wheel 23 keyed to the shaft 15. Means are provided for releasing the pawl 22 from its engagement with the ratchet, for yieldingly holding the pawl in one or another of its alternate positions, and for again throwing the pawl to ratchet engaging position. For thus releasing the pawl, it is provided with a finger 28, adapted, upon the upward movement of the pitman, to be tripped by means of a stop 29, adjustably secured in a slot-provided support 30. To hold the pawl in its alternate positions, there is provided a thrust bolt 26, held, by means of a spring 27, yieldingly against a suitable bearing face 24 of the pawl when the pawl is in operative position, and against a similar face 25 in the opposite position of the pawl. When out of engagement with the ratchet, it will be understood that the pawl 22 will be in about the position in which the finger 28 is indicated as being when the pawl is operative. To throw it into operative position, a second stop 31 is adjustably secured to the frame 30, and against which stop the pawl strikes on the downward or return stroke of the pitman. By such an arrangement the pawl may be rendered active during any suitable period of the cycle of operation of the machine to 60 advance the carriage any desired amount.

The pawl-and-ratchet connection for effecting each concluding movement of the carriage are similar in general construction to the connections just described. The end of the shaft 5 is provided with a crank arm 32, to which one end of a second pitman 33 is adjustably and pivotally secured, the other end of such pitman being pivotally attached to an arm 34, rotatably mounted on the shaft 15. A driving member, comprising a ratchet wheel 36 and one member of a friction clutch, is also rotatably mounted on such shaft. The driving-member part of the friction clutch consists of a frame or casing 37, secured to the ratchet wheel 36 as by bolts 42, and a plurality of plates 38, rotatable with the casing but slideable therein longitudinally of the shaft 15. The second member of the clutch consists of a collar 39, keyed to the shaft 15, and a plurality of plates 40, alternately arranged with the plates 38. The plates 40 are rotatable with the collar 39, but slideable longitudinally of the shaft 15; and, to adjust the pressure of the two series of plates upon each other, suitable springs 41 are provided. The arm 34 is provided with a pawl 43, held in engagement with the ratchet 36 by means of a spring 44. As will readily be seen, the two pawls 22 and 43 engage their respective ratchets 23 and 36 so as to turn them, and hence the shaft 15, in the same direction. No means are provided to disengage the pawl 43, so that, during the initial movement of the carriage, the shaft 15 is driven through both sets of pawl-and-ratchet connections. The concluding movement, however, is effected solely through the friction clutch, and the arrangement is such that the driving member continues to act after the driven shaft 15 has been arrested, thus becoming effective to absorb the rebound and shock incident to the stopping of the carriage.

In the driving connections illustrated in Figs. 3 and 4 but a single pawl-and-ratchet is employed, and it acts through a friction clutch to effect both the initial and concluding intermittent movements of the carriage. In this arrangement the driving member consists of a shaft 45, a ratchet 46 secured thereto, and one member of a friction clutch 47, similar to that illustrated in Fig. 6. The other member of the clutch drives a pinion 48, which meshes with a pinion 49, secured to the shaft 15. The ratchet 46 is driven through a pitman 50, secured to the power shaft 5 and to an arm 51 rotatably mounted on the shaft 45, and pawl 52 secured to such arm. Whether the driving connections of Figs. 1, 2, 5 and 6, or those of Figs. 3 and 4 be used will depend upon the conditions of service. In so far as the driving power acts through a yielding member to absorb rebound momentum and shock, both connections are the same.

The stopping mechanism for arresting the carriage of the machine shown in Figs. 1 and 2, may be of any desired construction. That shown herein is similar to the stopping mechanism illustrated and described in my United States Patent No. 908,819. In the machine of said figures, the detent drum, rather than being mounted on a shaft borne by the movable carriage as in said patent, is 5 arranged to arrest the carriage by stopping the rotation of the driven fixed shaft 15, and means for releasing the drum-engaging detents and for lifting the trip finger are coordinated with the power shaft 5, so that the 10 entire machine continues to operate automatically and intermittently until a complete line of holes has been punched in the blank of material. However, it will be understood that the stopping mechanism may 15 be such as is shown in Figs. 9 and 10, the carriage being driven in the manner already explained.

In the stopping mechanism shown particularly in Figs. 1, 7 and 8, the detent drum 53 is secured directly to the shaft 15, and a plurality of pawls 54 are rotatably mounted on a shaft 55. To prevent injury to the machine by the shock of the stopping impact, the shaft 55 is mounted between the 20 upper ends of a pair of levers 56, 56^a rotatably mounted on a shaft 57, the other ends of such levers being secured to a rod 58, to which in turn there is attached a rod 59 engaged by one end of a stiff compression 25 spring 60, which abuts at its other end against the housing 16. As in the above mentioned patent, the openings in the pawls 54 to receive the shaft 55 are somewhat larger than the diameter of such shaft, and 30 fingers 61, 61^a pivoted as at 62, and acting under the tension of springs 63, holds the pawls forwardly. A second pair of pivoted levers 64, 64^a is provided to hold the pawls 54 from engagement with the detent drum, 35 and, to such end, a latch 65 extends between the lower ends of these levers and is adapted to engage hooks 66, formed on the upper sides of the pawls. Such latch may be cast integrally with the fingers 64, 64^a.

50 The levers 64, 64^a are pivoted to a shaft 67 and are held under the tension of springs 68. For releasing the pawls 54, so that they may drop into engagement with the detents of the drum 53 and thus stop the 55 shaft 15, a rod 69 is rotatably mounted in arms 70 and 70^a, which are secured to a shaft 71. The end of the rod 69 adjacent to the carriage 11 is provided with a trip finger 72, which lies in the path of suitably 60 spaced tripping elements 76 which may be of various forms, as illustrated in my Patent No. 835,123, and are secured to the carriage 11. The other end of the rod 69 has secured thereto a depending arm 73, attached by 65 means of a link 74 to a second arm 75, se-

cured to the shaft 67. Thus, when a tripping element upon the advance of the carriage engages the finger 72, such finger is moved to turn the rod 69, which, through arm 73, link 74, and arm 75, turns the shaft 70 67, which shaft in turn moves the fingers 64, 64^a to release the latch 65, permitting the pawls to drop into engagement with the drum.

To disengage or release the pawls 54 from the drum 53, the shaft 71, which is rotatably mounted in suitable bearings 85, 85^a, secured to the frame 1, is provided with arms 85, 85^a, from the outer ends of which are suspended links 86, 86^a. A rod 87 extends between the lower end of such links and below the series of pawls 54. The shaft 71 is further provided with an arm 77, connected by a link 78 to a second arm 79, secured to one end of a shaft 80, which 85 shaft is rotatably mounted in bearings 81, 81^a, secured to the frame 1. Attached to the other end of this shaft is an arm 82, provided with a roller 83, which bears on a cam 84 secured to the shaft 4. The projecting portion of the cam 84 is in such position upon the shaft 4 that substantially at the end of the punching operation, and before the driving mechanism has become effective, arm 82 will be raised; and the raising of this arm will, through shaft 80, arm 79, link 78, arm 77, shaft 71, arms 85, 85^a, links 86, 86^a, and rod 87, be effective to raise the pawls 54 from their engagement with the drum 53 (such drum-engaging position 90 being indicated in dotted lines in Fig. 7), to the position indicated in full lines. Furthermore such rotation of the shaft 71 is effective, through arms 70, 70^a, to raise the rod 69, and hence the trip finger 72 above 105 the engaged stopping element 76. In the further rotation of the shaft 4 the connections for raising the pawls and trip finger returns to the positions in Fig. 7, and in 110 readiness for the next stopping of the carriage.

For further detailed explanation of the construction and operation of the stopping mechanism reference may be had to my earlier Patents No. 835,123 and No. 908,819. 115 The features of novelty of my present construction as compared to the disclosures of these patents, concern the pawl and trip-finger release mechanism, and its coördination with the power shaft and carriage driving mechanism.

After the completion of a punching operation the carriage may be moved rearwardly by means of a motor 88, which may be mounted on the housing 16, as shown in 125 Fig. 2. A cog wheel 89 is rotatably mounted on the driven shaft 15, and is provided with clutch teeth adapted to engage a clutch sleeve 90, rotatable with the shaft 15 but longitudinally slidable thereon, as by means 130

of the hand lever 91. A suitable chain 92 extends between the power shaft of the motor and the wheel 89, so that by moving the collar 90 into engagement with such wheel, 5 and releasing the pawls 22 and 43 of the driving connections, the motor may be run to move the carriage rearwardly. As an alternate construction, the motor for effecting the rearward drive of the carriage may 10 be mounted on the carriage itself. This may be accomplished, as in the machine of Figs. 9 and 10, by a motor 104 acting through the driving connections therein illustrated, and to be presently described.

15 Before describing the construction of the modification shown in Figs. 9 and 10, the operation of the above described machine will be explained. While this machine may be used for punching evenly spaced holes in 20 structural blanks, such as the plate 10, it is particularly adapted to punch irregularly spaced holes. In setting up the machine for a particular spacing, the shortest and the longest spacing intervals are first ascertained. 25 When the driving connections of Figs. 1, 2, 5 and 6 are employed, the pawl stop 29 is set in the frame 30 at such a point that the pawl 22 will be released from the ratchet 23 before the carriage has been 30 driven a distance equal to the shortest spacing interval; and the radial distance from the center of the shaft 5 to the point of connection of the pitman 33 to the crank arm 32 is so fixed that, after the pawl 22 has been 35 released, the carriage will be driven through the friction clutch a distance greater than the difference between the largest spacing interval and the distance the carriage is driven by the unyielding driving connec- 40 tions, that is, through pawl 22. By such adjustments only the yielding driving connections will, at the end of each spacing interval, be effective to drive the carriage, and such connection will, at each of the variable 45 spacing intervals, continue to act after the stopping has become effective. As already explained such continued action of the yielding driving connections absorbs the rebound of the carriage and effectively holds it 50 in a position for accurate punching; and it will be observed that the power for this purpose is, through the pitman 33, positively and unyieldingly taken from the continuously rotatable power shaft, so that the rebound momentum of very heavy movable carriages may be effectively absorbed. In 55 case the driving connections of Figs. 3 and 4 are employed the only adjustment necessary is that of the connection of the pitman 50 to the crank arm of shaft 5^a. This connection should be such as to drive the carriage a distance greater than the longest spacing interval.

60 In outlining a complete cycle of operation, it will be assumed, as a starting point,

that the stopping mechanism is in inoperative position and the punches withdrawn from the material. The first period of a single rotation of the power shaft 5 is, through pinions 17 and 18, pitman 19, arm 20, pawl 22, ratchet 23, shaft 15, pinion 14, and rack 13, effective to drive the carriage a distance less than the shortest spacing interval. The pawl 22 is then released (the finger 28 striking the stop 29); and the second period of rotation of shaft 5 drives the carriage to the end of the spacing interval, the connections to the shaft 15 being through crank arm 32, pitman 33, arm 34, pawl 43, ratchet 36 and the friction clutch member 80 shown in Fig. 6. The advancing carriage then causes a stopping element 76 to trip the finger 72, which, through rod 69 arm 73, link 74, arm 75, shaft 67, and levers 64, 64^a, moves the latch 65 from engagement with the pawls 54, thus causing the pawls to drop into engagement with, and prevent further rotation of, the detent drum 53. The further action of the carriage driving connections through the friction clutch becomes effective to absorb the rebound of the carriage. The third period of rotation of shaft 5 is effective, through the shaft 4 to bring the punches 3 into operation upon the plate 10. The fourth and last period of the single rotation of shaft 5 causes the punches 3 to rise, and effects a release of the stopping mechanism. The last mentioned step is accomplished through the projecting portion of cam 84, arm 82, shaft 80, arm 79, link 78, arm 77, shaft 71, arms 85, 85^a and rod 87, such rod being raised to lift the pawls 54. At the same time, the rotation of the shaft 71 is effective, through arms 70, 70^a and rod 69, to lift the trip finger 72 over the engaged stopping element. This position of the stop-releasing mechanism is partly illustrated in Fig. 1. As the projection of the cam 84 passes the roller 83 of arm 82, rods 69 and 87 are lowered so that the stopping mechanism is again in readiness for the next arresting of the carriage. 100 In Figs. 9 and 10 there is shown a different form of tool-operating machine wherein two means are provided for moving the work-carriage, one of such means being positive and unyielding and adapted to effect the initial movement, and the other driving means acting through a yielding member and adapted to effect the concluding movement and to absorb the rebound of the carriage. The punching machine may be of any suitable or well known construction, that shown herein consisting of a frame 93, in which there is a punching head 94, 105 provided with punching tools 95, and adapted to be reciprocated by the rotation of a shaft 96. The spacing carriage, instead of being driven by a fixed shaft as in the machine of Figs. 1 to 8, is provided with driv- 110

ing mechanism movable with the carriage, and the material to be punched is secured to and trails after the carriage. It will be unnecessary to explain in detail the driving 5 and stopping mechanism of the carriage shown herein for they are fully described in my United States Patent No. 1,068,465. It is sufficient to state that the supporting 10 table 103 is provided with tracks 97 for the carriage trucks 98, with a detent bar 99 adapted to be engaged by the pawls 100 of the carriage, and with a rack 101 engaged by a driven pinion 102 of the carriage. The driving of the carriage is accomplished by 15 means of a motor 104, connected by a chain 105 to a shaft 106, which is provided with a magnetic clutch 107 and a friction clutch 108. The driven member of the friction clutch is effective through pinion 109 and 20 110, shaft 111, pinions 112, and 113, and shaft 114, to drive the pinion 102.

While broadly the machine shown in Figs. 9 and 10 illustrates various modifications of carriage driving mechanism, as explained 25 in connection with the description of the machine of Figs. 1 and 2, in a more specific aspect the improvements of these figures consist in the provision of unyielding means for effecting the initial movement of a carriage 30 provided with yielding driving means. While various arrangements may be provided for this purpose, it is preferred that the unyielding driving mechanism be coordinated with the rotation of the punch power shaft 96. In the construction shown 35 herein the lower side of the carriage frame 115 is provided with a depending frame 116 adapted to be secured to an endless chain 117, extending substantially the full length 40 of the spacing table, and driven by means of pawl-and-ratchet mechanism connected to the shaft 96. The chain passes over two cog wheels 118 and 119, suitably supported at opposite ends of the table. To keep the 45 chain taut, the wheel 118 is mounted at one end of a lever 120, pivoted as at 121, and having its other end held yieldingly toward the punching machine by means of a spring 122. The cog wheel 119 is secured to a rotatable 50 mounted shaft 123, to which there is secured a ratchet wheel 124. Adjacent to such ratchet, and rotatably mounted on the shaft 123, is an arm 125, provided with a pawl 126, adapted to engage the ratchet 124, 55 and to which arm there is secured one end of a pitman 127, adjustably connected at its other end to a crank arm 129, secured to the shaft 96. As already explained, the pawl-and-ratchet driving mechanism is provided 60 to effect an unyielding initial advance of the carriage at each spacing interval, the purpose being to positively overcome the initial inertia and the resistance to the carriage due to burs formed on the material when 65 punched. Means are therefore provided to

release the pawl 126 from the ratchet 124 before the carriage has been driven a distance equal to the shortest spacing interval. For such purpose this pawl may be controlled the same as the pawl 22 of Fig. 5, 70 and such mechanism, although indicated in Fig. 9, need not be again explained.

In the operation of this machine, as far as concerns the construction specifically illustrated, the initial unyielding driving of the 75 carriage is effected through the pawl-and-ratchet connection and the chain 117. The coördination of these connections with the rotation of the shaft 96 is such that the carriage is moved upon the withdrawal of 80 punches from the material being punched. The operation of the driving means mounted on the carriage is fully described in said Patent No. 1,068,456 and need not be here repeated. It is sufficient to state that the 85 motor 104 runs continuously, and that the power therefrom is transmitted to the pinion 102 through the magnetic clutch 107 and the yielding friction clutch 108, and that when the carriage is stopped and the circuit 90 broken through the magnetic clutch 107, the momentum of the rotating adjacent and rigidly connected members of said clutches acts to absorb the rebound of the carriage.

It has already been explained that the 95 chain driving connections of Figs. 9 and 10 may be used in place of the rack of Figs. 1 and 2; that the double pawl-and-ratchet connections of Figs. 1, 2, 4 and 5 may be used to drive carriages such as shown in 100 Figs. 9 and 10; and that the motor of Figs. 9 and 10 may be used solely for the purpose of effecting a rearward or return drive of the carriage. It will be understood, however, that various other modifications of construction and arrangement may be used by those skilled in the art, without departing 105 from the spirit of my invention as defined in the appended claims.

This application is, as far as there is 110 common subject-matter in the two cases, a continuation of my application Serial No. 841,331, filed May 27th, 1914. In said earlier application I disclosed a machine substantially the same as that shown particularly in 115 Figs. 1 and 2 of my present application, but differing therefrom in that it did not include a second pawl-and-ratchet connection for effecting an initial unyielding starting of the carriage, nor did it include the full 120 detail construction of the stopping mechanism.

I claim as my invention:

1. In a tool-operating machine, the combination of a movable work-carriage; a rotatable power shaft; operative driving connections between said power shaft and the carriage including a driving member positively and unyieldingly rotatable by said power shaft, and a driven shaft; a yielding 130

clutch connecting said member to said driven shaft, and carriage stopping means operative while said driving member continues to rotate.

- 5 2. In a tool-operating machine, the combination of a movable work-carriage, a continuously rotating power shaft, a rotatable driving member, operative connections between said shaft and member to intermittently and positively drive the latter, a driven shaft for moving the carriage, a yielding clutch connecting said driving member to said driven shaft, and means operative to stop said carriage and driven shaft while said driving member continues to rotate and through said clutch to absorb the rebound of the carriage.
- 10 3. In a tool-operating machine, the combination of a movable work-carriage, a continuously rotating power shaft, a rotatable driving member, pawl and ratchet connections between said power and driving member imparting an intermittent rotation to the latter, a driven shaft for moving the carriage, a yielding clutch connecting said driving member to said driven shaft, and carriage stopping means operative to arrest the movement of the carriage while the driving member continues to rotate.
- 15 4. In a tool-operating machine, the combination of a movable work carriage; intermittently acting means effective, when the movement of the carriage is unrestrained, to drive the carriage predetermined equal spaces; and means for stopping said carriage before it has moved through one of said spaces, the continued action of the driving means thereby becoming effective to absorb the rebound movement of the carriage.

- 20 5. In a tool-operating machine, the combination with a tool, a work-carriage, and a power shaft; of operative connections from said shaft to the tool, a stopping mechanism for said carriage, and operative connections from said power shaft to said carriage, said last named connections being effective to drive the carriage when said stopping mechanism is inactive and to absorb the rebound momentum of the carriage when the stopping mechanism is active.

- 25 6. In a tool-operating machine, the combination with a reciprocating tool, a work carriage, and a power shaft; of operative connections from said shaft to the tool for an intermittent reciprocation thereof, operative connections from said power shaft to said carriage for intermittently advancing it, stopping mechanism for arresting the advance of the carriage, and operative connections from said power shaft to the stopping mechanism for releasing said mechanism.

- 30 7. In a tool-operating machine, the combination with a tool, a work-carriage, and a power shaft; of operative connections from

said shaft to the tool for reciprocating it, operative driving connections from said shaft to said carriage and including a rotary shaft, means effective upon the advance of the carriage for engaging and stopping said rotary shaft, and operative connection from said power shaft to said stopping means for releasing said means.

8. In a tool-operating machine, the combination with a tool, a work-carriage, and a power shaft; of operative connection from said shaft to, and for the reciprocation of, said tool; driving connections from said shaft to said carriage and including a rotary driven shaft, a detent drum secured to said driven shaft, stopping pawls effective upon the advance of the carriage for engaging said drum to arrest the movement of the carriage, and connections from said power shaft to, and for releasing, said pawls.

9. In a tool-operating machine, the combination with a tool, a movable work-carriage, and a power shaft; of tool-operating connections from said shaft to the tool, operative driving connections from said shaft to said carriage for advancing it, stopping mechanism for the carriage and including a trip finger adapted to be engaged by the advance of the carriage, and means operated by said power shaft for releasing said finger.

10. In a tool-operating machine, the combination with a tool, a movable work-carriage, and a power shaft; of tool-operating connections from said shafts to the tool, operative driving connection from said shaft to said carriage and including a rotary shaft, stopping mechanism adapted to engage and stop said shaft, a trip finger engageable by the advance of the carriage and adapted to render the stopping mechanism effective, and a single means operated by said power shaft for releasing said stopping mechanism and trip finger.

11. In a tool-operating machine, the combination with a tool, a movable work-carriage, and a power shaft; of a rotatable driving member, means coordinated with the power shaft for intermittently rotating said member, a driven shaft yieldably connected to said member and operatively engaging said carriage, a detent drum secured to the driven shaft, stopping pawls normally held from engagement with said drum, a trip finger for releasing said pawls and engageable by the advance of the carriage, and means coordinated with said power shaft for disengaging said pawls and releasing said trip finger.

12. In a tool-operating machine, the combination of a movable work-carriage, unyielding driving connections for effecting an initial movement, and yielding driving connections for effecting a further movement of said carriage.

13. In a tool-operating machine, the com-

bination of a movable work-carriage, means for effecting an initial movement, and separate means for effecting a further movement of the carriage.

5 14. In a tool-operating machine, the combination of a movable work-carriage, unyielding means for effecting an initial movement, and separate yielding means for effecting a further movement of the carriage.

10 15. In a tool-operating machine, the combination of a movable work-carriage, unyielding means for effecting an initial, and separate yielding means for effecting a concluding movement of the carriage, and

15 means for rendering the unyielding moving means ineffective during such concluding movement of the carriage.

16. In a tool-operating machine, the combination with a tool, a movable work-carriage, and a power shaft; of tool-operating connections from said shaft to the tool, operative and unyielding connections from said shaft to said carriage for effecting an initial movement thereof, and a further 25 means for effecting the concluding movement of the carriage.

17. In a tool-operating machine, the combination of a movable work-carriage, a power shaft, a driving shaft effective to 30 move said carriage, positively acting means

coördinated with said power shaft to effect an initial turning of the driving shaft, and yielding connections between said shafts to effect a further turning of the driving shaft.

18. In a tool-operating machine, the combination with a tool, a movable work-carriage, and a power shaft; of tool-operating connections from said shaft to said tool, a rotary driving shaft effective to advance said carriage, pawl-and-ratchet connections 35 from said power shaft to said driving shaft to give it an initial rotary movement, and a second and yielding pawl-and-ratchet connection between said power and driving shaft to give it a further rotary movement. 40 45

19. In a metal-punching machine, the combination of a reciprocatory punch, a movable work-carriage, stopping mechanism for said carriage, unyielding means for giving said carriage an initial movement after 50 an operative stroke of said punch, and yielding means for further advancing said carriage.

In testimony whereof I have hereunto set my hand.

GEORGE PAUL THOMAS.
